UNITED STATES PATENT OFFICE

WILLIAM E. MOORE, OF PITTSBURGH, AND GEORGE L. SIMPSON, OF CORAOPOLIS, PENNSYLVANIA, ASSIGNORS TO PITTSBURGH RESEARCH CORPORATION, OF PITTSBURGH, PENNSYLVANIA

ANNEALING FURNACE

Application filed December 2, 1931. Serial No. 578,582.

Our invention relates to improvements in furnaces for heat treating operations and to a method of operating said furnaces.

An important object of our invention is the provision of means for controlling the atmosphere in heat treating furnaces.

Another object of our invention is to provide means for excluding the outside atmosphere from the interior of the furnace.

10 A further object of our invention is to provide means to protect the furnace walls from the atmosphere maintained about the charge.

Still another object of our invention is to provide novel means for admitting the desired atmosphere to the furnace interior and to the charge, and for removing atmosphere from the interior of the furnace and from the charge.

15 A still further object of our invention is to provide a method and apparatus for changing the atmosphere of the furnace or of the charge with the least possible loss of gas and time.

Yet another object of our invention is the provision of a novel shield for the furnace charge, and improved sealing means therefor.

Other objects and advantages of our invention will be apparent during the course of the following description.

20 In the accompanying drawings which form a part of this specification and wherein like characters of reference denote like or corresponding parts throughout the same,

Figure 1 is a vertical sectional view of one form of furnace embodying our invention,

Figure 2 is a sectional view of a shield having an alternative form of sealing means,

Figure 3 is a sectional view of a furnace embodying a modified form of our invention,

Figure 4 is a similar view showing another form of our invention,

Figure 5 is a sectional view of a furnace embodying our invention in which an automatic pressure regulator is used,

Figure 6 is a longitudinal sectional view of a furnace having means for admitting gas to the interior thereof,

Figure 7 is a sectional view of a furnace 50 having a novel shield and packing,

Figure 8 is a similar view showing an automatic control valve on the shield, and,

Figure 9 is a detail view of a modified form of shield cover.

In the drawings, wherein for the purpose of illustration is shown a preferred embodiment of our invention, the numeral 10 designates a furnace hood having a base 11 extending through the bottom thereof. Sealing means 12 are interposed between the base and 55 furnace hood, and the roof of the hood is preferably, although not necessarily, removable. The particular furnace structure and the heating means therefor form no part of the present invention and are shown more or less diagrammatically in the several views. Other types of furnaces may obviously be employed.

In the form of the invention shown in Figure 1, the charge 13 is stacked upon the 70 hearth 11 which is preferably covered on its top with a metal plate 14. A metal shield or container 15 is arranged over the charge 13 and rests upon the plate 14. Any suitable sealing means may be provided between the 75 hearth plate 14 and the shield. In Figure 1 we have shown a heat resistant gasket 16 arranged in a matrix or groove extending around the shield. The gasket extends below the bottom of the shield and is preferably 80 circular in cross section, although other shapes may be used. The weight of the shield 15 forces the gasket into intimate contact with the plate 14 and effectively seals the 85 interior of the shield from the rest of the furnace.

In some cycles of heat treating it is desirable to anneal or heat treat metals under a controlled atmosphere, and when it is desired to remove the heating hood after the heating period for use on another charge, a shield such as shown at 15 is used to enclose the charge.

When metals are heated considerable gas, 90 occluded or absorbed in the material, is liberated, to be partially reabsorbed during the cooling period, which is undesirable. The pressure in the surrounding atmosphere may also disturb the desired distribution of the 95 partial pressures in a controlled atmosphere. 100

It is therefore desirable to remove these liberated gases from the vicinity of the metals being treated.

We have found that it is a distinct improvement to provide one or more controllable exits for the gases so that a flow of some desired gaseous atmosphere may be swept through the furnace or container to carry out of contact with the charge any of the 10 gases which may have been liberated from the charge during heating.

The base and cover may be provided with gas inlets and outlets, and in Figure 1 we have shown valved pipes 17 extending 15 through the walls of the hood 10 adjacent its top and bottom. Gas may flow continuously through the furnace hood and be controlled by the valves in the pipes 17. When the shield 15 is used, gas is admitted through 20 the pipe 18 which extends up through the base, interiorly of the shield. The shield is vented through its top by means of either of two valved pipes 19 and 20. Vent 19 extends to a point adjacent the lower end of the 25 shield, while vent 20 terminates adjacent the top of the shield.

When gas is admitted through pipe 18 it is desirable to remove the air or other atmosphere in the shield, and if this atmosphere 30 is lighter than the incoming gas it is vented through pipe 20, whereas if it is heavier than the incoming gas it is vented from the bottom of the shield through pipe 19. With this arrangement, the incoming gas tends to 35 force the atmosphere from the shield without becoming intimately mixed therewith, and consequently the shield may be filled in a short time and with a relatively small loss of the incoming gas.

40 When the shield 15 is being used, and it is desired to prevent any leakage of gas therefrom, the pipes 17 may be utilized in building up a pressure in the furnace hood to equal or slightly exceed the pressure with- 45 in the shield. This situation is desirable in cases where the gas used in the shield would attack the lining of the hood. The same re- 50 sult can also be obtained, in some cases, by controlling the pressure within the shield relative to the normal atmospheric pressure 55 in the furnace hood. This may be carried out by having the pressure within the shield equal to atmospheric or other pressure within the furnace, or slightly exceeding atmos- 60 pheric pressure, to prevent entrance of the furnace atmosphere, or slightly under atmos- 65 pheric or other pressure within the furnace to prevent escape of gas from the shield.

When the heating operation is completed, 60 the hood 10 with its heating elements 21 may be removed and the charge allowed to cool down under the protecting shield 15 and in the desired atmosphere. When a flow of atmosphere is maintained by leaving one of the 65 exits open and continually admitting gas to

the shield, the exits are closed when the hood 10 is removed, to maintain a constant atmosphere in the shield during the cooling down period and to prevent the entrance of air to the shield.

A pipe 22 may extend through the base 11 to allow a thermocouple 23 to be inserted in the charge interiorly of the shield, and a seal may be provided in the pipe 22 by means of an oil or liquid 23'. 70 75

In Figure 2 the base plate 14' is provided with upturned flanges 24 at its edges. The shield 15' fits within these flanges and is spaced therefrom. A sand or other seal 16' may be arranged in the space between the flanges 24 and the shield 15'. 80

In the form of our invention shown in Figure 3 the base plate 14 is provided with upturned outwardly inclined flanges 24' which serve as guides for the shield 15 when it is lowered into position on the base. 85

In filling a shield or furnace with gas, a large waste of gas has heretofore been experienced due to the turbulence caused by the entrance of the gas into the furnace atmosphere, and the consequent mixing of the gas with the atmosphere. This difficulty may be overcome by the construction shown in 90

Figure 3 in which the gas used is lighter than the normal atmosphere, as for example, ammonia gas. The gas is admitted at the top of the chamber in such manner as not to create turbulence and consequent mixing with the atmosphere. The gas is admitted through a relatively small pipe 25 which extends 95 through the base 11 and into the end of a larger inlet pipe 26 carried by the shield 15. A depression 27 in the base allows the use of a seal at the juncture of the pipes 25 and 26. The pipe 26 extends to the top of the shield 100 and has an enlarged flared upper end 28. The incoming gas is free to expand as it enters the pipe 26 and its velocity is greatly reduced by the flared end 28 where it enters the shield chamber. The gas fills the upper portion of 105 the chamber and forces the normal atmosphere out of the chamber between the shield and the base plate, as indicated by the arrows. There is very little turbulence and mixing, and a large saving of the gas is effected. 110 115

In Figure 4 is shown a construction suitable for use when the gas used is heavier than the normal atmosphere. In this case it is desirable to displace the residual atmosphere upwardly with as little mixture with the incoming gas as possible. The base plate 14 is provided with upstanding flanges 24, as in Figure 2, and the shield 29 rests on the base plate in spaced relation with the flanges 24. A suitable sealing material such as sand may be arranged in the space between the shield and the flange, although other forms of seals may obviously be used. The upper end of the shield is open and provided with a channel 30 extending about 120 125 the walls thereof. A cover 31 has a depend- 130

ing lip or flange which rests in the channel 30. Sealing material may be placed in the channel if desired.

5 A valved gas inlet pipe 25' extends through the base to a point within the confines of the shield 29 and has its end flared. The gas is admitted through pipe 25' and displaces the residual atmosphere which leaks out between the cover flange and the channel 30 as indicated by the arrows. The displaced atmosphere can escape from the furnace hood through the flared, valved exit 32 in the top of the hood, or through one of the other pipes.

10 It will be seen, then, that to prevent turbulence and mixing of the incoming gas with the residual atmosphere, gas heavier than the residual atmosphere is admitted at the bottom of the chamber through enlarged or flared openings while gas lighter than the residual atmosphere is admitted through a flared opening at the top of the chamber. Where a shield is used, the pressure of the gas within the shield is adjusted with relation to the atmosphere in the furnace hood to prevent escape of the gas

20 from the shield or to prevent entrance of the hood atmosphere to the shield chamber. The shield may be dispensed with entirely, and the gas admitted directly to the furnace hood. Where no shield is used, and the hood is not sealed gas-tight, the desired adjustment of the furnace atmosphere relative to the outside atmosphere may be made to prevent escape of the furnace atmosphere or entrance of the outside atmosphere.

25 In place of relying upon the escape of the atmosphere or gas between the parts, such as the shield and base plate, or the shield cover and channel, openings may be provided for this purpose as seen at 57 in Figure 9. In place of adjusting the atmosphere within the shield to the furnace atmosphere, the furnace atmosphere may be adjusted relative to the atmosphere in the shield chamber, as by means of the valve pipes 33 in Figure 4.

45 In practice, the shield may be lowered over the pack of material on the hearth. The desired atmosphere is introduced through the flared inlet opening, and displaces the residual air which leaks out of the shield as shown in Figures 3 and 4. The furnace heating cover 10 is then lowered into position and the inlet valve adjusted with the outlet valve 32 in Figure 4 or 34 in Figure 3 to maintain the desired pressure within the furnace chamber, which may be equal to or slightly above the atmospheric pressure on the shield. As the furnace heats up and the atmospheres expand, the external and internal pressures are so regulated as to prevent the atmosphere in the shield from entering the furnace chamber. This is desirable in cases where the gas used will attack the refractory material of the furnace walls.

50 Where the atmosphere used does not have this deleterious effect, no precaution need be

taken to adjust the pressures, the excess from the inner shield merely leaking out into the furnace chamber, and passing out to the external atmosphere through pipe 32 in Figure 4 or 34 in Figure 3.

70 Whether or not a shield should be used depends upon the materials treated and the atmospheres used. Where the atmospheres will react upon the metal shield, no shield is used, as for example, in nitriding crank shafts where ammonia gas is used, it has been found that the use of a metal shield unfavorably affects the operation due to the action of the ammonia on the metal shield, which results in the treated work being less hard, and requiring the use of larger amounts of ammonia than when no metal is exposed to the atmosphere used. It is desirable to enclose the charge in a shield where the atmospheres used will attack the furnace walls, or where it is desired to cool the work in a controlled atmosphere, while at the same time removing the heating hood for additional work.

75 The use of one or more gas inlets so designed as to reduce to a minimum the tendency for the incoming gas to mix with the air in the shield has proved to be a very valuable expedient, and has saved much time and gas in actual practice. If the gas is admitted through the usual pipes, there is a high velocity and the incoming gas is thoroughly stirred into the air already in the shield or furnace. Complete displacement of the residual air can only be accomplished by venting a large quantity of this mixture, which entails a great loss of the incoming gas. On the other hand, if the desired atmosphere is introduced without turbulence and at a reduced velocity, there is very little disturbance in the residual air, and the full effect of the density difference of the two atmospheres is obtained in clearing the shield of air and replacing it with the desired atmosphere with a minimum waste of the incoming gas. Gases such as ammonia, hydrogen and helium are introduced at the top of the container. Heavy gases such as carbon dioxide, nitrogen and the like are introduced at the bottom of the container or furnace chamber.

80 100 105 110 115 120 In Figure 5 is shown a furnace having an automatic control of the differential pressure between the atmospheres in the furnace and in the shield. Higher than normal pressures may be maintained in the shield without leakage by applying this pressure control. As sand seals are not absolutely gas tight, liquid or compound seals should be used at 12 between the base and furnace hood.

125 The furnace construction shown in Figure 5 is similar to that illustrated in Figure 3, although other forms of shields and gas inlets and outlets may obviously be used, such as those shown in Figure 4. A gas outlet pipe

70

105

110

115

120

125

130

35 has a flared end extending through the base and communicating with the interior of the shield, and gas enters the shield through the pipes 25, 26 and flared end 28. An in-
5 let pipe 36 communicates with the upper portion of the furnace hood and an outlet pipe 37 communicates with the lower portion of the furnace hood.

The outlet pipe 35 communicates with a
10 pressure responsive device illustrated dia-
grammatically at 38 and the outlet pipe 37
communicates with a pressure responsive de-
vice illustrated diagrammatically at 39. A
valve 40 in the inlet pipe 36 is operatively
15 connected to the device 38 by a bar 41 and
a valve 42 in the inlet pipe 25 is connected to
the device 39 by a bar 43. A lever 44 is piv-
oted at its center and is connected adjacent
20 its ends to the bars 41 and 43. Adjustment
is secured by adjusting the connection be-
tween the valve arms and the bars 41 and 43
which are provided with a plurality of con-
necting openings for this purpose. Pressure
25 in the shield operates through pipe 35 and
device 38 to control the inlet valve 40 to the
furnace chamber, and pressure in the furn-
ace chamber operates through pipe 37 and
device 39 to control inlet valve 42 to the shield
30 chamber. It will be seen, therefore, that a
constant pressure difference may be main-
tained automatically in the two chambers by
means of the pressure responsive devices
35 38 and 39 which also affect one another
through the pivoted lever 44. This construc-
tion operates automatically, and overcomes
pressure differences caused by heating and
cooling, and by escape of atmosphere from
40 one chamber to the other.

In Figure 6 is shown a furnace construc-
45 tion for admitting gas to a furnace chamber
without causing turbulence and mixing of the
incoming gas with the furnace atmosphere.
The gas conduit communicates with a mani-
fold 45 which communicates with a plurality
50 of diffuser nozzles 47 in the top of the furnace
hood. The displaced air escapes at the bot-
tom of the furnace in any suitable manner, as
by means of a plurality of valved outlets 48.
This arrangement of a plurality of diffuser
55 nozzles connected by a manifold may be used
with any of the furnaces shown, and located
in the furnace hood or in the base for use with
or without a shield. This construction is
highly desirable when dealing with gases such
60 as hydrogen or natural gases which form
explosive mixtures with air. As mixing is re-
duced to a minimum, the time required for
thoroughly gassing out the chamber, for turn-
ing on the power without danger of an explo-
sion due to the presence of residual air, is
greatly reduced. Rapid gassing out of a
shield is also facilitated by the construction
shown in Figures 3 and 4 in which the resid-
ual atmosphere escapes about the entire edge
65 of the shield, at the top in Figure 4 and at the

bottom of the shield in Figure 3, and conse-
quently is not delayed in its escape.

In Figure 7 is shown a furnace in which the
base 14 is provided with an upstanding lip
70 or flange 24 similar to that shown in Figures
2 and 4. The shield 49 is provided with an
inverted channel 50 around its lower edge
which receives a gasket 51. The gasket ter-
minates short of the lower edge of the channel
75 50 and rests on the lip 24 which extends up
into the channel, the weight of the shield forc-
ing the gasket into intimate contact with the
lip 24.

The gasket seal shown in Figure 7 is su-
perior to the usual sand seal in that it permits
80 uniform heating of the shield and base plate.
The sand seal usually employed is open to the
objection that it acts as a heat insulator and
keeps the lower edge of the shield at a lower
85 temperature than the top of the shield, and
the consequent unequal expansion results in
twisting and warping of the shield. With the
uniform temperature present in the shield 49,
there is no tendency to warping of the shield,
90 as the lower edge of the shield is exposed di-
rectly to the heat of the resistor 21.

In Figure 8 the shield is similar to that
shown in Figure 7 although other types of
shields may obviously be used. Gas is ad-
mitted to the shield through inlet pipe 25' and
95 discharged from the furnace through valved pipe 33. An opening 52 is arranged
in the top of the shield and allows the escape
of gases from the shield chamber into the
furnace chamber. A valve 53 normally closes
100 the opening 52 and is supported by one arm
of a bell crank lever 54 pivoted at 55 to the
top of the shield. A plate or trigger 56 is se-
cured to the underside of the furnace roof and
engages the other arm of the lever 54. The
105 weight of the valve normally maintains its
closed position over the opening 52. When
the furnace hood 10 is lowered onto the base
11, the trigger 56 engages the bell crank lever
110 and raises the valve into the open position
shown in Figure 8. In this position, gases
may escape from the shield. When the heat-
ing period is over and the hood 10 is removed,
the weight of the valve automatically closes
115 it, and air is prevented from entering the
shield. This construction obviates the dif-
ficulties encountered when a gas tight shield
was used, in which accumulated moisture and
obnoxious gases caused staining or scaling of
120 the sheets during the cooling down period.
With the present construction, however, mois-
ture, steam and obnoxious gases are released
during the heating period but the shield is
automatically sealed when the heating hood is
125 removed.

The valve 53 may be made of heat resisting
material and may be provided with a gasket
if desired.

Although we have described our invention
as applied to heat treating and annealing op-
130

erations, we contemplate applying it to other operations and to other types of furnaces.

While we have shown and described the preferred embodiment of our invention it is to be understood that various changes in the size, shape and arrangement of parts, and in the steps of our method may be resorted to without departing from the spirit of our invention or the scope of the subjoined claims.

10 Having thus described our invention, what we claim and desire to protect by Letters Patent is:

1. In a heat treating furnace, a base, a heating hood therefor, a shield adapted to rest on said base, said shield having a groove carried at its lower edge, and a gasket arranged in said groove and adapted to engage said base.

2. In a heat treating furnace, a heating hood, a base therefor, a base plate arranged on said base, a shield adapted to rest on said base plate, said shield having a groove carried at its lower edge, and a gasket arranged in said groove and adapted to engage said base plate.

3. In a heat treating furnace, a base plate having upturned edges, a shield adapted to rest on said plate in spaced relation to the upturned edges, and a sealing material arranged between the shield and the upturned edges of the base plate.

4. In a heat treating furnace, a base plate, a shield adapted to rest thereon, said shield having a groove carried at its lower edge, and a gasket arranged in said groove and extending therebelow, said gasket being adapted to engage the base plate.

5. In a heat treating furnace, a base adapted to receive a charge, a heating hood therefor, a base plate on said base having upturned edges, a shield adapted to be arranged over said charge and rest on said base plate, and sealing means between the upturned edges of the base plate and the shield.

45 6. In a heat treating furnace, a base plate having an upturned flange therearound, a shield therefor, said shield having an inverted channel around its lower edge, and a gasket in said channel adapted to engage the upturned flange of the base plate.

7. In a heat treating furnace, a base plate having an upturned flange therearound, a shield therefor, said shield having an inverted channel around its lower edge, and a gasket in said channel adapted to engage the upturned flange of the base plate and terminating short of the lower edge of the inverted channel, whereby the base flange extends into said channel to engage the gasket.

55 8. In a heat treating furnace, a base, a removable heating hood therefor, a shield arranged within said hood, and a valve-controlled opening in said shield.

9. In a heat treating furnace, a base, a removable heating hood therefor, a shield ar-

ranged within said hood, said shield having an opening therein, a valve adapted to close said opening, and means operated by the placement of the hood on the base to open said valve.

10. In a heat treating furnace a base adapted to support a charge, a removable heating hood for said base, a shield arranged on said base and adapted to cover said charge, said shield having an opening therein, a valve pivoted to the shield and normally closing said opening, and means operated by the placement of the hood on the base to move the valve about its pivot to uncover the opening in the shield.

11. In a heat treating furnace, a base adapted to support a charge, a removable heating hood for said base, a shield arranged on said base and adapted to cover the charge, said shield having an opening therein, a lever pivoted intermediate its ends to the shield, a valve carried by said lever and adapted to normally close said opening, and means on the heating hood to engage said lever and move the valve away from the opening.

12. In a heat treating furnace, a base adapted to support a charge, a removable heating hood for said base, a shield arranged on said base and adapted to cover the charge, sealing means between the base and shield, means to admit a gaseous atmosphere to said shield, said shield having an opening therein, means normally covering said opening, and means operated by the placing of the hood on the base to uncover said opening.

13. In a heat treating furnace, a base adapted to receive a charge, an open top shield arranged over said charge and resting on said base, said shield being adapted to receive a gaseous atmosphere and having a channel arranged about its upper end, and a shield cover having a depending lip adapted to rest in said channel and having openings adjacent the lower edge thereof to form a tortuous outlet for the gaseous atmosphere in said shield.

14. In a heat treating furnace, a base, a heating hood therefor, means to admit a gaseous atmosphere to said hood, and means to gradually and progressively reduce the velocity and diffuse the incoming atmosphere as it enters the hood to reduce turbulence and mixing of the incoming atmosphere with the residual atmosphere.

15. In a heat treating furnace, a base, a heating hood therefor, and means to admit a gaseous atmosphere to said hood comprising a gas inlet pipe communicating with the interior of the hood, said pipe having its end progressively enlarged as it approaches the interior of the hood.

16. In a heat treating furnace, means to admit a gaseous atmosphere to the furnace comprising a gas inlet pipe having a gradually and progressively enlarged and flared

70

115

120

125

130

diffuser nozzle communicating with the interior of the furnace, and means of exit for the residual atmosphere displaced by the incoming gaseous atmosphere.

5 17. In a heat treating furnace, means to admit a gaseous atmosphere to the furnace comprising a plurality of flared diffuser nozzles communicating with the interior of the furnace, a manifold connecting the diffuser nozzles, and a gas conduit communicating with the manifold.

10 18. In a heat treating furnace, means to admit a gaseous atmosphere to the furnace comprising a plurality of flared diffuser nozzles communicating with the interior of the furnace, a manifold connecting the diffuser nozzles, a gas conduit communicating with the manifold, and means to permit the escape of the residual atmosphere displaced by the incoming atmosphere.

15 19. In the operation of a heat treating furnace, the method of gassing out the furnace which comprises displacing the residual atmosphere in the furnace by forcing a gaseous atmosphere into the furnace while substantially preventing mixture of the gaseous atmosphere with the residual atmosphere.

20 20. In the operation of a heat treating furnace, the method of gassing out the furnace which comprises admitting a gaseous atmosphere to said furnace, gradually and progressively reducing the velocity of the gaseous atmosphere as it enters the furnace and removing the displaced residual atmosphere.

25 21. In the operation of a heat treating furnace, the method of gassing out the furnace which comprises admitting a gaseous atmosphere to said furnace to displace the residual atmosphere of the furnace and progressively reducing the velocity of the gaseous atmosphere as it enters the furnace.

30 22. In the operation of a heat treating furnace having a charge container therein, the method of replacing the atmosphere in the charge container which comprises admitting a gaseous atmosphere to said container, while permitting the escape of the displaced residual atmosphere from the container and while substantially preventing turbulence and mixture of the incoming gaseous atmosphere with the residual atmosphere.

35 23. In the operation of a heat treating furnace having a charge container therein, the method of replacing the atmosphere in the charge container which comprises admitting a gaseous atmosphere to the container, and gradually and progressively reducing the velocity of the gaseous atmosphere as it enters the container, while permitting the escape of the displaced residual atmosphere.

40 24. In the operation of a heat treating furnace, the method of replacing the residual atmosphere with a heavier gaseous atmosphere which comprises admitting the heavier gaseous atmosphere adjacent the bottom of

the furnace and allowing the displaced residual atmosphere to escape adjacent the top of the furnace.

45 25. In the operation of a heat treating furnace, the method of replacing the residual atmosphere of the furnace with a heavier gaseous atmosphere which comprises admitting the heavier gaseous atmosphere at a low velocity and in a substantially diffused condition to the lower portion of the furnace, while permitting the escape of the displaced residual atmosphere from the upper portion of the furnace.

50 26. In the operation of a heat treating furnace, having a charge container therein, the method of replacing the residual atmosphere of the container with a heavier gaseous atmosphere which comprises admitting the heavier atmosphere at a low velocity to the lower portion of the container while permitting the escape of the displaced residual atmosphere from the upper portion of the container.

55 27. In the operation of a heat treating furnace, the method of replacing the residual atmosphere with a lighter gaseous atmosphere which comprises admitting the lighter gaseous atmosphere to the upper portion of the furnace while permitting the escape of the displaced residual atmosphere from the lower portion of the furnace.

60 28. In the operation of a heat treating furnace, the method of replacing the residual atmosphere of the furnace with a lighter gaseous atmosphere which comprises admitting the lighter gaseous atmosphere at a low velocity and in a substantially diffused condition to the upper portion of the furnace while permitting the escape of the displaced residual atmosphere from the lower portion of the furnace.

65 29. In the operation of a heat treating furnace having a charge container therein, the method of replacing the residual atmosphere of the container with a lighter gaseous atmosphere which comprises admitting the lighter atmosphere at a low velocity to the upper portion of the container while permitting the escape of the displaced residual atmosphere from the lower portion of the container.

70 30. In the operation of a heat treating furnace, the method of treating a charge which consists in continuously flowing a gaseous atmosphere past the charge during the heating period, and maintaining a substantially constant atmosphere about the charge during the cooling period.

75 31. In the operation of a heat treating furnace, the method of treating a charge which comprises supplying a gaseous atmosphere to the furnace, and maintaining a substantially constant pressure difference between the furnace atmosphere and the outside atmosphere.

32. In the operation of a heat treating furnace having a charge container therein, the method of treating a charge which comprises supplying a gaseous atmosphere to the charge container, and maintaining a substantially constant pressure difference between the atmosphere of the container and the furnace atmosphere.

33. In the operation of a heat treating furnace having a charge container therein, the method of treating a charge which comprises supplying a gaseous atmosphere to the container, and controlling the container atmosphere and the furnace atmosphere to maintain a substantially constant pressure difference therebetween.

34. In a heat treating furnace having a charge container therein, means to supply a gaseous atmosphere to the container, and means to control the pressure difference between the container atmosphere and the furnace atmosphere.

35. In a heat treating furnace having a charge container therein, means to supply a gaseous atmosphere to the container, means to control the furnace atmosphere, and means to control the pressure difference between the container atmosphere and the furnace atmosphere.

36. In a heat treating furnace having a charge container therein, means to supply a gaseous atmosphere to the container, means to supply a gaseous atmosphere to the furnace, and pressure operated means to control the pressure difference between the container atmosphere and the furnace atmosphere.

In testimony whereof we affix our signatures.

WILLIAM E. MOORE.
GEORGE L. SIMPSON.
